(57) **CLAIM**

The ornamental design for an extended wear hearing device main module, as shown and described.

DESCRIPTION

FIG. 1 is a front elevation view of the extended wear hearing device main module of the present invention;

FIG. 2 is a left elevation view thereof;

FIG. 3 is a rear elevation view thereof;

FIG. 4 is a right elevation view thereof;

FIG. 5 is a top perspective view of the extended wear hearing device main module;

FIG. 6 is a bottom perspective view of the extended wear hearing device main module;

FIG. 7 is a top elevation view of the extended wear hearing device main module; and,

FIG. 8 is a bottom elevation view thereof.
